UNITED STATES PATENT OFFICE.

JAMIESON V. SCAIFE, OF McCOMB, MISSISSIPPI.

GAGE-COCK.

1,031,380.

Specification of Letters Patent.

Patented July 2, 1912.

Application filed July 6, 1911. Serial No. 637,274

To all whom it may concern:

Be it known that I, JAMIESON V. SCAIFE, a citizen of the United States, residing at McComb, in the county of Pike and State 5 of Mississippi, have invented certain new and useful Improvements in Gage-Cocks, of which the following is a specification.

My invention relates to improvements in gage cocks and refers particularly to that 10 class of gage cocks used upon steam boilers for determining the water level.

The leading object of my invention is the provision of a device of this character which will obviate the difficulties and disadvantages of cocks now in general use, and more particularly my invention is designed as an improvement upon the gage cock patented by me October 18, 1910, No. 973,074, and which I have found to be unsatisfactory in 20 a few minor details. The present invention is designed to overcome these objections and broadly stated my improvement resides in the provision of a sleeve and compressible coiled spring slidably mounted in a sleeve 25 cap or casing, and this construction replaces the separate skeleton portion or member of my former patent.

My invention further consists in the provision of a device of the character described 30 which will embody novel features of construction and combination of parts for service, substantially as disclosed herein, and in order that my invention may be fully understood and its many advantages appreciated I have illustrated in the accompanying 35 drawings a practical embodiment of my device in which—

Figure 1 represents a longitudinal sectional view of the complete device. Fig. 2 40 represents a detail view of the sleeve cap or casing. Fig. 3 represents a detail view in section of the slidable sleeve and flange which forms one of the most important features of my invention, and Fig. 4 represents an end 45 elevation of the rim or flange shown in Fig. 3.

In the drawings in which similar characters of reference denote corresponding parts in the several views: The numeral 1 designates the body portion or member of my 50 gage cock, of cylindrical shape, and having the screw-threaded end 2 for engagement with the corresponding screw-threads of the steam boiler. Extending centrally through the said portion 1 is the cylindrical bore or 55 passage 3 having at one end the opening 4

and at its other end the valve seat 5, having the free end of a cylindrical valve rod 6 ground to form a frusto-conical portion 7 adapted to be snugly seated upon the said 60 valve seat. Extending downwardly therefrom and at substantially right angles to the body portion 1 is the branch or nipple 8, having the axial opening 9, communicating with the valve seat and passage, the passage 65 3, valve seat 5, valve rod 6 and nipple 8 being incased in the socket or joint 10. Arranged forwardly of said socket 10 is the externally threaded portion 11, engaging the corresponding internally threaded cylindrical casing 12, having the nut 13, adapted to receive a wrench or other tool for removal, and arranged in said casing 12 is a suitable form of packing 14, adapted to be held in place by a washer 15. Arranged in said cylindrical casing 12 is a sleeve 16 internally threaded to engage the externally threaded portion 17 of said valve rod 6, and said sleeve 16 has integrally formed on one end the flange or rim 18, which is adapted to 70 engage the said washer 15 to retain same in place against the packing. Mounted in an annular chamber 19 in said cylindrical casing 12 and entirely surrounding the sleeve 16 is a coiled spring 20, having one end abutting against the rim or flange 18 on said sleeve and its other end retained by the inwardly extending flanges 21 of the said casing 12. From this construction it will be seen that the said sleeve 16 and flange 18 75 are adapted to be moved longitudinally along the threaded portion 17 of the valve rod 6 and furthermore that the coiled spring 20 retains the valve in proper position. The rim or collar 18 is provided with a notch or 80 kerf 18' formed upon its outer edge into which is adapted to be engaged a lug or rib 19' projecting from the inner wall of the housing or casing. This construction prevents the revolution of the sleeve 16 when 90 the valve rod 6 is rotated. The forward end of the valve rod 6 is mounted in the hand wheel 22, by means of which the valve rod 100 may be turned.

In operation it will be seen that upon the 105 rotation of the valve rod 6 and the subsequent unseating thereof, the water will be free to pass through the opening 4 into the opening 9, and when the valve is seated upon the valve seat 5, the flange or rim 18 110 of the sleeve 16 is out of engagement with the washer 15 in the cylindrical casing 12,

and that the coiled spring 20 retains the said sleeve and hence the valve rod in its seated position upon the valve seat 5. It will also be noted that rotation of the valve rod will 5 cause the automatic grinding of the frustoconical portion 7 upon the seat 5, and furthermore that all wear between the valve seat and portion 7 will be taken up by the spring 20 and sleeve 16.

10 From the foregoing it will be apparent that I have provided a device for the purpose stated which will overcome the objections to the gage cocks in present usage; which will be of extremely simple and inexpensive construction; and which will be entirely practical and efficient from every 15 point of view.

I claim:

1. In a gage cock, the combination with a 20 housing and a threaded valve rod, of a threaded sleeve carried by said rod, a nut formed integral upon one end of said sleeve, a washer mounted in said housing forward of the integral nut on the sleeve, and a 25 coiled spring interposed between the sleeve and the housing and intermediate the said nut and the rear wall of the housing.

2. In a gage cock, the combination with a 30 housing and a threaded valve rod, of a threaded sleeve carried by said rod, said sleeve consisting of a longitudinally extending portion having a nut formed integral therewith and disposed at right angles there-

to, a washer carried by the valve rod forward of the integral nut and adapted to 35 abut against said nut, and a coiled spring entirely surrounding the longitudinally extending portion of the sleeve and intermediate the said nut and the rear wall of the housing. 40

3. In a gage cock, the combination with the body portion having the central passage therethrough, the valve seat, the nipple communicating with and at right angles to said valve seat, the interiorly threaded cylindrical housing, the nut carried thereby, the packing arranged in said housing at its forward end, the washer disposed rearwardly of the packing and adapted to retain same in place, the longitudinally extending externally threaded rotatable valve stem, the interiorly threaded sleeve carried thereby, the integrally formed nut carried by said sleeve at its forward end, the coiled spring surrounding the said sleeve and stem intermediate the rear wall of the housing and the integrally formed nut of the sleeve, and the hand wheel at the rear end of the stem for rotating same and unseating the valve from its seat. 45 50 55 60

In testimony whereof I affix my signature in presence of two witnesses.

JAMIESON V. SCAIFE.
